UNITED STATES PATENT OFFICE

158,458

COMBINED SAVINGS BOX AND PICTURE FRAME

Axel Werner Gullstrand, Stockholm, Sweden

Application February 3, 1949, Serial No. 670
In Sweden December 6, 1948

Term of patent 7 years

(Cl. D34—11)

To all whom it may concern:

Be it known that I, Axel Werner Gullstrand, manufacturer, a subject of the King of Sweden, and a resident of Stockholm, Sweden, have invented a new, original, and ornamental Design for a Combined Savings Box and Picture Frame, of which the following is a specification, reference being had to the accompanying drawing, forming part thereof.

The single figure is a perspective view of a combined savings box and picture frame, showing my new design.

The dotted line showing of a representative photograph is for illustrative purposes only:

I claim:

The ornamental design for a combined savings box and picture frame, as shown and described.
AXEL WERNER GULLSTRAND.
